BUILDING BLOCK

Miles E. Freeman, Saratoga Springs, N. Y.

Application January 9, 1941, Serial No. 373,840

3 Claims.

(Cl. 72—41)

My invention relates to building blocks of the general type forming the subject matter of my U. S. Patent No. 2,174,875 dated October 3, 1939, and over which the instant invention is designed as an improvement.

The principal object of the present invention is to provide inexpensive, durable, hollow blocks for building a wall with heat and cold insulation air space and with concealed cement or mortar joints between the blocks.

Another object is to provide building blocks adapted for cementing to form concealed joints, and for rubbing in the joints to render the same tight.

To the accomplishment of the above and the subordinate objects presently appearing, a preferred embodiment of my invention has been illustrated in the accompanying drawings, set forth in detail in the succeeding description, and defined in the claims appended hereto.

In said drawings:

Figure 1 is a view in perspective of a portion of a wall built of blocks constructed in accordance with the preferred embodiment of my invention.

Figure 2 is a view in perspective of one of the corner blocks.

Figure 3 is a similar view of another corner block.

Figure 4 is a view in longitudinal section.

Figure 5 is a view in vertical transverse section taken on the line 5—5 of Figure 4.

Figure 6 is a view in horizontal section taken on the line 6—6 of Figure 4, and

Figure 7 is a view in perspective of one of the side wall blocks.

Referring to the drawings by numerals, the present invention comprehends side wall blocks 1 and corner blocks 2, 3, which are designed to be laid end to end in staggered relation and may be made of any suitable material but are preferably of glass or other transparent material.

The side wall blocks 1 are rectangular and each formed with open ends and bottom, side walls 4, and a top wall 5 provided with a longitudinally centered rectangular slot 6 therein. The side walls 4 extend above the top wall 5 to provide a pair of longitudinally extending upper edge tongues 7 upon opposite sides of the block, respectively. The top wall 5 is provided with a rectangular bead 8 thereon extending around the slot 6 and of the said height as said tongues 7. The bead 8 and tongues 7 form a countersink, or well, in the top of the block 1 for holding mortar, or cement, and the slot 6 provides an open top

5 in the block for circulation of air vertically through the wall. The side wall blocks 1 at one end thereof are rabbeted externally to form with the top 5 a key extension 10 on said end of the block and at the opposite end of the block the side walls 4 are internally rabbeted, as at 11, and the top is set back, as at 12, so that adjoining side wall blocks 1 may be laid end to end with the key extension 10 of one interfitting in one 10 end of the other and the tops and side walls fitting flush.

The side walls 4 of each side wall block 1 are rabbeted externally along the bottoms thereof to provide a pair of bottom tongues 13 on said 15 side wall, whereby said walls of one block 1 are adapted to fit flush on the tongues 7 of a subjacent side wall block with the tongues 13 thereof fitting in between the tongues 7 and thereby interlocking with the subjacent block against 20 lateral play being freely slid able endwise along the subjacent blocks.

With a row of side wall blocks 1 laid end to end and keyed together, as above described, for instance, on a cement base 14, mortar or cement, 25 represented at 15 in Figures 4 and 5, may be poured onto the tops 5 of the blocks of said row to substantially the level of the tongues 7 and beads 8 and another row laid on top of the base row and each block of the new row rubbed endwise 30 in the cement, or mortar, to effect a tight concealed joint in a manner which will be clear.

The corner blocks 2, 3, are designed to form end blocks for right angularly laid rows of side wall blocks 1 and to be laid crosswise of each 35 other. Each corner block 2, 3, is of rectangular form with side walls 16, a top wall 17 and an end wall 18, said blocks being open at their bottom and one end and the side walls and end wall, in each instance, extending above the top 40 wall 17 to provide upper edge tongues 19 on said side walls, and also on the end wall 18 for a purpose similar to tongues 8, as will presently be apparent, the side and end walls 16, 18, of each corner block 2, 3, are externally rabbeted to 45 provide bottom tongues 20 for fitting into a subjacent corner block. One side wall 16 of block 2 from substantially the transverse center thereof to the end wall 18 is set back, as at 21, or countersunk, and provided with a pair of vertical beads 22 so that the rabbeted end 11 of a side wall block 1 may be interfitted therewith and the bead 19 of said side wall 16 is provided 50 with a gap 23 therein so that the tongues 20 of a corner block laid on top and crosswise thereof may be keyed in said block 2 and fit flush on the

top wall 17 of the same across half of said top wall. At its open end the side walls 16 of the corner block 2 are internally rabbeted and the top wall 17 set back just as in the case of the side wall blocks 1 to receive the key extension 10 of a side wall block 1 laid adjacent said end of said block 2. As will be understood, the tongues 19 of corner block 2 provide for interfitting of one end of a side wall block 1 on the top of said block 2 against one side of a corner block laid across said block 2. Adjacent the open end of the corner block 2, the top wall 17 is slotted, as at 24, and beaded, as at 25, just as in the case of the side wall blocks 1 and for the same purpose. As will be understood, a corner block and 15 a side wall block 1 laid on top of corner block 2 may both be rubbed into the mortar, or cement, on the top wall 17 to form a tight concealed joint.

The other corner block 3 has one side wall 16 cut out, as at 26, to establish communication between the interior thereof and a side wall block 1 laid endwise against the same and said side wall is stepped, or rabbeted, vertically, as at 27, for fitting therein of the key extension 10 of a side wall block 1 laid endwise to the same. Adjacent its closed end 18 the top wall 17 of corner block 3 is slotted, as at 28, and beaded, as at 29, for the same purpose as the slot and bead of side wall block 1 and slot 24 and bead 25 of corner block 2. Otherwise, the corner block 3 is constructed in the same manner and for the same purpose as described with reference to corner block 2.

The foregoing will, it is believed, suffice to impart a clear understanding of my invention without further explanation, since the manner in which the blocks are laid and the advantages thereof has been set forth in connection with the description of the construction of the same.

Manifestly the invention, as described, is susceptible of modification without departing from the inventive concept, and right is herein reserved to such modifications as fall within the scope of the subjoined claims.

What I claim is:

1. A building block of the type to be laid in rows comprising an elongated body open at one end and the bottom thereof, respectively, and including a top and side walls, respectively, said top being slotted to permit air to pass vertically through the block, the side walls extending above said top to provide key tongues along the same and said top having a raised bead surrounding said slot of the same height as said key tongues and forming together with said tongues a depression in the top of the block extending around said bead to receive cement, said side

walls being externally rabbeted along the bottom edges thereof to fit between and upon the key tongues of a correspondingly formed subjacent block, one end of said block having a key extension around the side walls and top thereof for fitting into one end of another block, the end of which is rabbeted to accommodate said key extension.

2. A building block of the type to be laid in rows comprising an elongated body open at one end and the bottom thereof, respectively, and including a top and side walls, respectively, said top being slotted to permit air to pass vertically through the block, the side walls extending above said top to provide key tongues along the same and said top having a raised bead surrounding said slot of the same height as said key tongues and forming together with said tongues a depression in the top of the block to receive cement, said side walls being externally rabbeted along the bottom edges thereof to fit between and upon the key tongues of a correspondingly formed subjacent block, one side wall of said block having a pair of transverse grooves therein for receiving an end extension of another mating block laid endwise against said side thereof, the key tongue of said one side wall having a gap therein to permit the rabbeted bottom edges of another correspondingly formed block laid crosswise thereon to fit flush on the top thereof.

3. A building block of the type to be laid in rows comprising an elongated body open at one end and the bottom thereof, respectively, and including a top and side walls, respectively, said top being slotted to permit air to pass vertically through the block, the side walls extending above said top to provide key tongues along the same and said top having a raised head surrounding said slot of the same height as said key tongues and forming together with said tongues a depression in the top of the block to receive cement, said side walls being externally rabbeted along the bottom edges thereof to fit between and upon the key tongues of a correspondingly formed subjacent block, one side wall of said block having a pair of transverse grooves therein for receiving an end key extension of another mating block laid endwise against said side thereof, the key tongue of said one side wall having a gap therein to permit the rabbeted bottom edges of another correspondingly formed block laid crosswise thereon to fit flush on the top thereof, said one side wall being apertured to establish communication between the interior of said block and said mating block laid endwise against said side.

MILES E. FREEMAN.
